G. A. YANOCHOWSKI

TELEPHONE SYSTEM

Original Filed April 25, 1917

UNITED STATES PATENT OFFICE.

GEORGE A. YANOCHEWSKI, OF CHICAGO, ILLINOIS, ASSIGNOR TO KELLOGG SWITCH-BOARD AND SUPPLY COMPANY, OF CHICAGO, ILLINOIS, A CORPORATION OF ILLINOIS.

TELEPHONE SYSTEM.

Application filed April 25, 1917, Serial No. 164,318. Renewed June 2, 1922. Serial No. 565,405.

To all whom it may concern:

Be it known that I, GEORGE A. YANOCHEWSKI, a citizen of the United States of America, residing in Chicago, county of Cook, and State of Illinois, have invented certain new and useful Improvements in Telephone Systems, of which the following is a specification.

My invention relates to link circuits for 10 telephone systems, being directed more particularly to link circuits having automatic ringing, secret service and automatic listening, peg count, and flash recall.

One of the objects of my invention is to 15 provide a link circuit of the above character in which five relays only are used for controlling the supervisory and secret service system, and also the peg count and automatic ringing system. Other objects of my 20 invention will be hereinafter more particularly pointed out.

I have preferably embodied my invention in an operator's cord circuit, and in carrying out my invention when applied to the 25 five relay arrangement, I employ an answering supervisory relay which is energized when the answering terminal of the cord circuit is connected to a calling line whereby the operator's telephone is connected in circuit with the calling substation. A second 30 relay is provided in the nature of an operator's disconnect relay which operates when the calling terminal of the cord circuit is connected to a called line, the operation of 35 the relay effecting the disconnection of the operator's telephone. A third relay in the nature of a ringing control relay is provided which is adapted to be energized upon 40 a response from the called substation to disconnect the ringing current from the called line. A fourth relay is provided to automatically switch the circuit of the answering 45 supervisory lamp from a continuous source of current to an interrupted source of current, a fifth relay in the nature of a calling supervisory relay is provided by which a called substation controls a calling supervisory signal.

For a better understanding of my invention, reference is to be had to the accompanying drawing in which two telephone lines L and L¹ are shown, the called line being of the party line type and having a plurality of substations connected thereto. 55 Each of the line circuits includes a line

relay LR and a cut-off relay CO together with multiple jacks J, the calling circuit L having its parts indicated by large reference characters and the called line circuit L¹ having its parts indicated by large reference characters with the suffix prime (') added.

The operator's cord circuit C is adapted for interconnecting the telephone lines and has an answering plug P and a calling plug P¹ connected by so-called tip and sleeve conductors having the condensers K¹ and K² interposed. A relay AS is associated with the answering terminal of the cord circuit and serves as an answering supervisory relay, and also operates as an operator's connect relay to connect the operator's telephone set O with the link circuit when a call is answered. An answering supervisory signal SS is controlled by the answering supervisory relay AS and by the flash recall relay FR. The relay AS which is controlled over the calling line is connected to one terminal of the central office telephone battery, the other terminal of the battery being connected through an impedance coil D to the other strand of the link circuit so as to bridge the central office battery across the talking conductors of the answering end of the link circuit for talking and supervisory purposes. An operator's disconnect relay OD is connected to the calling terminal of the link circuit and operates to disconnect the operator's telephone from the link circuit when the calling plug P¹ is connected to the called line.

Owing to the fact that the operator's telephone is connected through normally closed contacts of relay OD, it will be apparent that as long as the plug P¹ is in connection with a link circuit the operator's telephone O is disassociated with the link circuit, giving so-called secret service in which the operator cannot listen in during a connection between two telephone lines. The operation of relay OD is also effective to connect ringing current from one of the ringing generators of the ringing apparatus H to the terminals of the called line, and when a response is secured from the substation on this line the ringing control relay RCR is operated to disconnect the ringing current therefrom. The upper winding 4 of the ringing control relay RCR is adapted to be included in the path for the ringing current

by a non-inductive shunt winding 5, preferably wound upon the core of said relay RCR, and provides a more ready path for the ringing current when the called line is being signalled. When applying ringing current to the called line, it is preferable to disconnect the answering end of the link circuit from the calling end so that the ringing current will not flow back over the calling line, and to provide this feature I provide contacts controlled by the relay RCR which are included in the talking strands of the link circuit. To prevent the application of the ringing current after the called subscriber has responded and replaces his receiver upon its switch hook, I provide a locking winding 6 for relay RCR so that when it once energizes it will remain energized until the relay OD is deenergized by the disconnection of the plug P from the jack of the called line. To make the relay RCR sensitive and still have sufficient attracting power to perform its work, I arrange the contact springs 7 to make before the other springs are operated, thereby closing a local energizing circuit for winding 6 of relay RCR at which time the continued attraction of the armature of relay RCR operates the other springs controlled by said relay. An advantage of such an arrangement is that this relay which is initially energized over the called line circuit starts the attraction of its armature under the tension of but a single contact spring until this local contact circuit is closed, after which the other springs are operated, and in this way a comparatively large number of contacts may be operated by a relay which is initially controlled over the subscriber's line circuit, which may vary considerably in resistance.

A calling supervisory signal SS¹ is associated with the calling plug P¹ and is caused to glow when the plug P¹ is inserted into the jack J¹ to the called line, and is effaced when the called subscriber responds by removing his receiver from its switch-hook.

To economize upon space, I combine the impedance coil D and the calling supervisory relay CS in one structure whereby I secure an evenly balanced talking circuit, that is, at the answering end of the cord circuit a full winding is connected to the tip side and a half winding to the sleeve side while at the calling end a half winding is connected to the tip side and a full winding to the sleeve side of the circuit. The impedance winding D is non-inductive and does not affect the magnetic circuit of the calling supervisory relay CS. If it is desired, the magnetic circuit of winding CS may be entirely isolated from winding D although included in the same structure.

65 When applying my invention to party line

ringing, I provide a well known form of party line indicating key having contact sets 11, 12, 13 and 14, corresponding in number to the number of frequencies, these contacts being closed when the plungers are in their intermediate locking and indicating position.

In the preferred method of operation, the proper ringing plunger is depressed before the calling plug P¹ is inserted into a jack, this arrangement being preferred because in using a locking party line ringing key one of the ringing contacts is always closed so that I prefer to select the desired frequency before the plug is inserted into the called jack. Preferably, I provide the well known ringing system which includes four ringing generators, 15, 16, 17 and 18, which generate ringing current of the required frequencies to operate the call bells at the party line substation telephones. Each of the ringing generators is connected through a periodically closed contact, there being, therefore, four such contacts 19, 20, 21 and 22, which may be operated by any source of power to periodically close the ringing contacts 23, 24, 25 and 26.

In order to insure the operation of relay RCR when the receiver is removed at the called substation, I provide a source of direct current 27 in connection with the ringing device H, which source is preferably a separate source from the talking battery, and may consist of dry cells, and has one of its poles grounded so that when the vibrating contacts 19, 20, 21 and 22 are closed during the silent interval this battery is connected in series with the cord circuit battery, giving a higher potential so that a more positive operation of relay RCR is secured.

From inspection, it will be apparent that the peg count device K, by which the number of answered calls by each operator is recorded, comprises a relay 28 of high resistance and impedance which is common to each operator's position and which is adapted to be energized each time a calling plug P of its corresponding position is inserted in the jack of a subscriber's line to answer a call. The operation of the relay 28 closes a circuit through a meter magnet 29 which operates to record the call upon a meter.

The flash recall relay FR, which controls the flashing and the supervisory lamp SS when a recall is desired, is provided with a locking circuit that after once being closed maintains the relay FR energized until the calling plug P¹ is disconnected from the jack of the calling subscriber's line. The relay FR controls the association of the interrupter I with the supervisory lamp SS.

Now having described in general the embodiment of my invention as illustrated, its operation will now be described.

Assuming a subscriber at substation X has removed his receiver to initiate a call,

the line relay LR is energized over the calling line in a well known manner to operate the associated line signal S, whereupon the operator inserts an answering plug P into 5 a jack J of the calling line, establishing an energizing circuit for cut-off relay CO and supervisory relay AS. The operation of the cut-off relay CO is effected by a circuit traced from battery through the winding 10 of impedance coil D, answering sleeve conductor, sleeve contacts of the plug and jack, and the winding of relay CO to ground. This circuit does not affect the armature of relay CS. The relay CO energizes over 15 this circuit and operates to disconnect the line relay LR and extends the conductors of the line X to the answering end of the cord circuit. The receiver at the calling substation being off its hook, there is a flow 20 of current through impedance coil D and out over the called line returning over the tip side of the cord circuit and through the winding of the answering supervisory relay AS to ground. Relay AS energizes 25 over the above-traced circuit and interrupts its normal contacts 30 and 31 so that the lamp SS cannot be operated until the calling subscriber has replaced his receiver. A further result due to the energization of relay AS is the connection of operator's telephone O to the strands of the link circuit 30 through its alternate contacts 32 and 33.

The closing of the alternate contact 32 of relay AS also closes a circuit for the 35 meter-controlled relay extending from battery through the non-inductive winding D of relay CS, through normal contact 34 of relay OD, through alternate contact 33 of relay AS and the winding of the relay 28 to ground. The relay 28, upon energizing, closes a circuit for the meter control magnet 29 traced from battery through the winding of said magnet 29 and through alternate contact 60 of relay 28 to ground. The 45 magnet 29, upon energizing, operates to register a call upon the counting mechanism.

The operator now inquires the number of the desired subscriber and tests the jack J¹ of the called line by applying the tip conductor of the plug P¹ to the bush of a jack of the called line in the usual manner and finding the line idle inserts said plug P¹ into the said jack J¹ after having pressed the proper ringing button of the ringing apparatus H. The connection of plug P¹ to the jack J¹ closes an energizing circuit for the disconnect relay OD and the cut-off relay CO¹, causing the energization of these relays by current over a circuit traced from 50 battery through the winding of OD, sleeve contacts of plug P¹ and jack J¹ and the winding of cut-off relay CO¹ to ground. The operation of relay CO¹ removes the substation control of line relay LR¹ in the 55 usual manner, and the operation of relay

OD effects the disconnection of the operator's telephone O by reason of the interruption of normal contacts 34 and 35.

A further result due to the energization of relay OD is the closing of a circuit for 70 calling supervisory lamp SS¹ over a circuit traced from ground through alternate contact 36 of relay OD and through normal contact 37 of relay CS and said lamp SS¹ to battery. A still further result due to the 75 energization of relay OD is the application of ringing current to the called line by reason of the closing of alternate contact 38, the path for ringing current being traced from generator 15, (which we will assume 80 is a selected generator by reason of its operated contact 11) through alternate contact 23, alternate contact 11, ringing conductor 40, windings 4 and 5 in multiple, alternate contact 38 of relay OD, normal 85 contact 41 of relay RCR, tip side of the link circuit over the called line, including the substation call bell, returning over the sleeve conductor to point 42 where the current divides, part of it flowing through relay OD 90 and battery to ground, and part of it flowing through normally closed contact 43 and winding 44 to battery and to ground.

Each periodical closure of alternate contact 19 of the ringing device H, of course, 95 causes an operation of the call bell, and when the called subscriber responds by removing his receiver in response to the call and upon the following closure of alternate contact 45 of the ringing device, due to the 100 removal of the condenser at the substation, a path for direct current through the winding 4 of the ringing control relay RCR is established to cause the initial energization thereof.

As already stated, when the contact 45 is closed, ringing battery 27 is connected in series with the cord circuit battery, providing a higher potential for operation of the ringing control relay than if only the cord 105 circuit talking battery is used. This circuit may be traced from battery 27 through alternate contact 45, over the previously described path for ringing current, and back through the relay OD and winding 44 in 110 multiple to the cord circuit battery. The flow of current through the initial energizing winding 4 of relay RCR causes the attraction of its armature, whereby its contacts 7 are first closed to bring the local 115 energizing winding 6 in circuit to cause the continued attraction of the armature which 120 interrupts normal contacts 41 and 43, thereby disconnecting the ringing current and closing alternate contacts 41 and 43 to 125 establish the continuity of the talking circuit. The closing of alternate contact 41 connects the calling supervisory relay CS in circuit with the line so that battery flowing through the relay OD and out over the 130

called line returns over the tip side of the link circuit, through alternate contact 41 of relay RCR, and winding of said relay CS to ground. The relay CS, upon energizing, operates to interrupt its normal contact 37, thereby effacing the calling supervisory lamp SS¹. It will also be noted that relay RCR interrupts its own initial energizing circuit through its normal contacts 41 and 43 but not until its local circuit is closed.

The substations X and Y are now connected in conversational circuit, the talking battery being fed over the heavily marked conductors to the calling and called line. During the connection of the link circuit with the calling and called lines, it is impossible for the operator to listen in to the conversation, due to the fact that her telephone has been disconnected from the link circuit by reason of the interrupter contacts 34 and 35 of relay OD and cannot again be closed until the plug P¹ is withdrawn from the connected jack J¹. After the subscribers have finished their conversation, they will replace their respective receivers upon their switch hooks, this act at the calling substation X causing the restoration of answering supervisory relay AS and thereby closing the energizing circuit for the answering supervisory signal SS and the flash recall relay FR, while the restoration of the receiver at the called substation Y causes the restoration of the calling supervisory relay CS, thereby closing a circuit for the calling supervisory lamp SS¹. The circuit for answering supervisory lamp SS extends from battery through said lamp, armature 50 and contact 30 of relay AS, and through alternate contact 36 of relay OD to ground. The circuit for flash recall relay FR extends from battery through the winding of said relay FR, contact 31, armature 50, and contact 30 of relay AS, and through alternate contact 36 of relay OD to ground.

Relay FR upon energizing, closes a locking circuit for itself through its alternate contact 51, independent of the armature 50 of relay AS. The locking circuit for relay FR extends from battery through winding of relay FR, its alternate contact 51, and through alternate contact 36 of relay OD to ground. The circuit for the calling supervisory lamp SS¹ extends from battery through the said lamp SS¹, normal contact 37 of relay CS and through alternate contact 36 of relay OD to ground.

The operator in response to the glow of supervisory lamps SS and SS¹ removes plugs P and P¹ from their respective jacks, the withdrawal of plug P¹ causing the de-energization of relay OD and by reason of the interruption of alternate contact 36 effects the restoration of relay RCR, the withdrawal of plug P causing the restoration of

relay CO. The apparatus of cord circuit C is now at normal and the cord circuit is available for use in establishing other connections.

Should the subscriber at substation X desire to make a recall before the plugs P and P¹ of cord circuit C have been withdrawn from their respective jacks, he removes his receiver from its switch hook, thereby again closing an energizing circuit for relay AS over the circuit herein-before traced. Relay AS this time upon energizing switches the circuit of the calling supervisory lamp SS from ground at alternate contact 36 of relay OD to interrupted ground supplied by the interrupter I over a circuit traced from battery through said supervisory lamp SS, armature 50 and contact 56 of relay AS, alternate contact 57 of relay FR, and through the interrupter I to ground. The interrupter I causes the supervisory lamp SS to be flashed intermittently to notify the operator that a recall is desired by the calling subscriber and that she should give this call her immediate attention. The operator now removes the calling plug P¹ from the jack J¹ of the called subscriber's line, thereby permitting the relay OD to de-energize and again connect the operator's telephone set O to the strands of the link circuit to inquire the wants of the calling subscriber. At the same time that the operator's set is again connected to the strands of the link circuit, the locking circuits for relays FR and RCR are opened at contact 36 of relay OD. The operator after receiving the desired information from the calling subscriber completes the connection with the desired called line in the same manner as herein-before described.

Had the calling subscriber initiated a recall before the called subscriber responded, the relay FR alone would have been de-energized when the operator removed the called plug P¹ from the jack of the called subscriber to reconnect her telephone set O to the strands of the cord circuit. The replacing of the receivers at the calling and called subscribers' substations operates the supervisory signals in the same manner as herein-before described.

From the foregoing, it will be apparent that I am enabled to accomplish the following features: automatic ringing, secret service and automatic listening, flash recall and peg count with the provision of only five relays to a cord circuit.

While I have illustrated a preferred embodiment of my invention, it is apparent that it may be applied in various ways and also that many modifications and changes will readily suggest themselves to those skilled in the art. Therefore, I do not desire to be limited to the exact structure as shown, but aim to cover all that which comes

within the spirit and scope of the appended claims.

What I claim as new, and desire to secure by United States Letters Patent is:

5. 1. A telephone system including subscribers' telephone lines, an operator's link circuit for interconnecting said lines, a control relay controlled over a connected subscriber's telephone line, an operator's telephone, circuits controlled directly by said control relay for connecting said operator's telephone to said link circuit, an auxiliary relay, a circuit for said auxiliary relay adapted to be closed by the de-energization 10 of said control relay, a locking circuit for said auxiliary relay independent of its energizing circuit, a supervisory lamp, and a circuit for said supervisory lamp including contacts of said auxiliary and control relays and adapted to be closed when said relays are both energized. 15
2. In a telephone system the combination with a subscriber's telephone line and a link circuit connected thereto, a relay controlled over said subscriber's line, an operator's telephone, circuits controlled directly by said relay for connecting and disconnecting said operator's telephone and said link circuit, a supervisory signal and an auxiliary relay, 20 circuits for said supervisory signal and said auxiliary relay adapted to be closed by the de-energization of said first relay, and a second circuit for said supervisory signal including contacts of said first relay and 25 said auxiliary relay and adapted to be closed when both of said relays are energized. 30
3. A telephone system comprising telephone lines, a link circuit provided with only five relays for interconnecting said lines, ringing apparatus and a pair of supervisory signals for said link circuit, one of said relays being adapted to control one of said supervisory signals, the second of said relays adapted to connect the ringing apparatus to a called subscriber's line, the third of said relays adapted to disconnect the ringing current from the called subscriber's line, the fourth of said relays adapted to directly control the other of said supervisory 40 signals, and the fifth of said relays adapted to include an interrupter in circuit with said first supervisory signal to indicate that a recall is desired. 45
4. A telephone system including telephone lines, a link circuit provided with only five relays for interconnecting said lines, ringing apparatus and a pair of supervisory signals for said link circuit, one of said relays being adapted to control one of said supervisory signals, the second of said relays adapted to connect said ringing apparatus to a connected telephone line, the third of said relays adapted to disconnect said ringing apparatus from said subscriber's line, 50 the fourth of said relays adapted to directly 55
- close a continuously operating circuit for said other supervisory signal, and the fifth of said relays being controllable by the fourth of said relays for closing an intermittently operating circuit for said last supervisory signal. 70
5. In a telephone system the combination with a subscriber's telephone line, of a plugged link circuit connected therewith, a single wound relay for said link circuit controllable over said subscriber's telephone line, an operator's telephone, circuits controlled directly by said relay for connecting and disconnecting said operator's telephone and said link circuit, a supervisory signal, a continuously operating circuit for said signal adapted to be closed by the de-energization of said relay, and an intermittently operated circuit for said supervisory signal including contacts of said relay and adapted 75 to be closed by the re-energization of said relay. 80
6. A telephone system including a subscriber's telephone line, a link circuit, a relay for said link circuit adapted to be connected to said telephone line, a supervisory signal, a movable and three relatively stationary contacts for said relay, a continuously operating circuit for said signal including said movable and one of said stationary contacts, 90 an intermittently operated circuit for said signal including said movable and another of said stationary contacts, and an auxiliary relay connected to the third of said stationary contacts, energized upon the de-energization of said first relay for controlling a contact in said intermittently operated circuit. 95
7. In a telephone system including an operator's link circuit, a relay for said link circuit, a movable and three relatively stationary contacts for said relay, an auxiliary relay, a supervisory signal, a continuously operating circuit for said supervisory signal including said movable and one of said stationary contacts, a circuit for said auxiliary relay including another of said stationary contacts and adapted to be closed upon the de-energization of said first relay and an intermittently operated circuit for said 100 supervisory signal including said movable and the other of said stationary contacts and a contact controlled by said auxiliary relay. 110
8. A telephone system including a calling and a called subscriber's line, a link circuit for connecting said lines in conversational circuit, an operator's telephone, automatic means for connecting and disconnecting said operator's telephone and said link circuit, a pair of supervisory signals, means for controlling continuous circuits for said signals and for closing an intermittently operating circuit for one of said signals, and means for automatically ringing said called sub- 120 125 130

scriber, all of said above means being controlled by only five relays.

9. A telephone system including a calling and a called subscriber's line, a link circuit provided with only five relays for connecting said lines in conversational circuit, said link circuit being provided with automatic listening, flashing recall, automatic ringing and automatic disassociation of the ringing current from the called line, all of said features being controlled by said five relays.

10. A telephone system including a calling and a called subscriber's line; a link circuit provided with only five relays for connect-

ing said lines in conversational circuit; said link circuit being provided with means for automatically connecting an operator's telephone with said link circuit, for intermittently operating a supervisory signal, for automatically connecting to and ringing the called subscriber's call bell, and for automatically disassociating said ringing means from said called substation; said means all being controlled by said five relays. 15

Signed by me at Chicago, in the county 25 of Cook and State of Illinois, this 23d day of April, 1917.

GEORGE A. YANOCZOWSKI.
